FIG.5

FIG. 1 is a plan view of an expandable link chain for a bracelet showing my new design;

FIG. 2 is a side elevation of the chain illustrated in FIG. 1;

FIG. 3 is a plan view of the chain shown in FIG. 1, partly expanded;

FIG. 4 is an enlarged longitudinal sectional view taken on line 4—4 of FIG. 3; and

FIG. 5 is an enlarged transverse sectional view taken on line 5—5 of FIG. 3.

The dominant features of my design reside in the portion shown in full lines.

I claim:

The ornamental design for an expandable link chain for a bracelet or the like, as shown and described.
